United States Patent Office.

CHARLES ANTHONY, OF PROVIDENCE, RHODE ISLAND.

Letters Patent No. 90,148, dated May 18, 1869.

IMPROVEMENT IN RIGGING FOR GAFF-TOPSAILS.

The Schedule referred to in these Letters Patent and making part of the same.

To all whom it may concern:

Be it known that I, CHARLES ANTHONY, of the city and county of Providence, and State of Rhode Island, have invented a new and improved Mode of Hanging and Securing Gaff-Topsails of Vessels; and I do hereby declare that the following is a full, clear, and exact description of the same, reference being had to the accompanying drawings, making part of this specification, in which—

Figure 1 is an elevation of the top-mast and gaff of a vessel, with the top-sail set thereon, in accordance with my improved mode.

Figure 2 is a detached view of the top-mast and upright spar, and the hangings of the same.

Figure 3 is a section of the gaff and its spar, and the hangings and fastenings of the same.

Similar letters indicate corresponding parts in all the figures.

My said invention is designed more particularly for the smaller class of "fore-and-aft" rigged sailing-vessels, yachts, fishing-smacks, and the like, in which the top-sail is attached to an upright spar, to which the halyards, or hoisting-line is attached, and runs through a block secured at the mast-head, from which the sail hangs, or is suspended, while the free corners of the sail are attached to other halyards, or lines, one of which passes through an eye, or block at the peak of the gaff, and all of which are hauled taut to set the sail from the deck of the vessel, and are finally secured at the foot of the mast.

By this mode of hanging the top-sail, its entire weight, together with the strain produced by its resistance to the wind, is sustained by the single rope by which the top-sail is hoisted to its place, which so stretches the rope throughout its entire length as to require it to be frequently set up to keep the sail snugly against the mast, and prevent it from flapping when "sailing on the wind," and this severe strain, together with the motion of the sail in tacking, chafes and wears the halyards where it passes through the block, and makes it liable to part and let the sail loose from its hangings, most frequently while the vessel is sailing, and makes it necessary to ascend to the mast-head to reeve the halyard through the hoisting-block, and secure its end again to the spar of the top-sail before it can be set in its place.

My invention is calculated to overcome these and other difficulties, and to afford a more substantial hanging and fastening, and a more perfect means of setting the top-sail in a permanent position from the deck, than any hitherto employed, to my knowledge.

My invention, to this end, consists in hanging the gaff-topsail by means of a step and pintle arranged between the upright spar and the top-mast, and with suitable halyards, in such a manner that the sail may be hoisted, and hung upon its pintle and step, from the deck of the vessel, and, when thus hung, the hal-

yards are relieved of all strain, and all chafing in the block, or otherwise, avoided; and

My invention further consists in securing the top-sail permanently to the peak of the gaff by means of a metallic latch-link, operated by halyards from the deck, passing through an eye in the end of the gaff, in such a manner that the metal link is drawn through the eye, and locked therein by the latch, and the halyards thereafter relieved from all strain upon them.

In the said drawings—

S is the top-sail, having an upright spar, J, and another spar, F, extending outward from above the gaff G.

The spar J has a stout wrought-iron pintle, P, near its middle, extending upwards through a wrought-iron eye, D, on the top-mast N.

The lower end of said spar is furnished with a pintle, T, which steps into an eye, E, lower down upon the top-mast. The spar J and the sail hang and swing freely upon these two pintles.

The halyards A are made fast to an eye in the end of the pintle P, and pass through the eye D and the block O, and thence to the foot of the mast.

The halyards H are made fast to an eye in the end of the pintle T, and pass through the eye E, and thence to the foot of the mast, as shown in part in fig. 2.

In setting the top-sail, it is hoisted to its place by the halyards A, which draws the pintle P through its eye D, when, by drawing the halyards H taut, the pintle T is brought into line with the eye E, and drawn down into it by slackening the upper halyards A, when the sail is securely hung on the two pintles, and both halyards may be secured at the foot of the mast, leaving the sail hanging, independently of any support from either, by the pintles P and T. The lower halyards H should, however, be set taut, to prevent the lower pintle from lifting from its step in the eye E.

The outer free end of the top-sail may terminate at or near the end of the gaff, at the point marked R, and have an eye in the corner of the sail, by which to connect it with the gaff, as is ordinarily the case; or the sail may be secured to the spar F, as shown in the drawings. In either case, the sail may be secured to the gaff by a stout iron link, K, having a latch, or lever, f, to the long arm of which are attached the halyards L, passing through a stout metal eye, V, near the end of the gaff; and after the top-sail is hung upon its pintles, in the manner described, it is further set by drawing the halyards L through the eye V, until the latch and a portion of the link are drawn through, when, by carrying the halyards from a position at which the latch may draw through the eye V, in line with the link, as illustrated by the arrow W, fig. 3, towards the foot of the mast, to attain the position illustrated by the arrow X, in fig. 3, whereby the latch f is placed crosswise of the link beneath the eye V, and thus looks the link in the eye, and holds this part

of the sail permanently to the gaff, at least until this link is again unlocked, at the same time relieving the halyards from further strain.

To free this part of the sail, for the purpose of furling it, or taking it in, it is only necessary to haul the halyards L taut, and draw the latch f into line with the link, when the whole will readily slip through the eye V, and permit the sail to be hauled down.

It will be seen that the top-sail, by this mode of hanging, is permanently secured by the pintles P and T, and the link K, to the top-mast and gaff, without any dependence upon the halyards, which simply serve, in this connection, to control the said pintles and latch-link, by which alone the sail hangs; also, that swinging upon said pintles, the sail always preserves the same relative position to the mast as the main-sail, and, in consequence, is held more closely to the point of the wind to which the main-sail is set, than would

be possible with the uncertainty of the old mode, which depends upon the tautness of the hoisting-halyards, and that, besides this, all chafing of the ropes is avoided.

Having described my invention,

What I claim, and desire to secure by Letters Patent, is—

The mode described of hanging and securing the gaff- topsail to the mast and gaff by means of the pintles P T and the latch-link K, or their equivalent, operated by halyards from the deck of the vessel, substantially as specified.

In testimony whereof, I have hereunto subscribed my name, this 15th day of February, 1869.

CHARLES ANTHONY.
